UNITED STATES PATENT OFFICE.

ALDEN M. DRAKE, OF HARTFORD, CONNECTICUT.

CHANGEABLE-SPEED FEED MECHANISM.

No. 824,914.

Specification of Letters Patent.

Patented July 3, 1908.

Application filed January 29, 1906. Serial No. 298,367.

To all whom it may concern:

Be it known that I, ALDEN M. DRAKE, a citizen of the United States, residing at Hartford, in the county of Hartford and State of Connecticut, have invented a new and useful Changeable-Speed Feed Mechanism, of which the following is a specification:

This invention relates to a changeable-speed feed mechanism for screw-cutting and similar machine tools.

The object of the invention is to provide a simple self-contained mechanism which can be readily applied to any common form of screw-cutting lathe or similar machine having a cutting-tool the rate of feed of which it is desirable to frequently change, which mechanism is constructed of simple parts that drive positively and directly with a minimum amount of friction and wear, thus economizing power and insuring long life and accurate work, and which is so arranged that without danger of jamming or injuring any of the parts it can be instantly set to obtain any one of a large number of different speeds by the simple movement of a handle.

Figure 1 of the accompanying drawings shows a side elevation of the head of a screw-cutting lathe provided with a changeable-speed feed mechanism which embodies this invention. Fig. 2 shows an end elevation of the same. Fig. 3 shows a section taken through the changeable-speed gearing on the plane indicated by the dotted line 3 3 on Fig. 2. Fig. 4 shows a section of the gearing on the plane indicated by the dotted line 4 4 on Fig. 2. Fig. 5 shows an end view of the gearing represented in Fig. 4. Fig. 6 shows a horizontal section on the plane indicated by the dotted line 6 6 on Fig. 2. Fig. 7 shows a vertical section on the plane indicated by the dotted line 7 7 on Fig. 1:

The changeable-speed feed mechanism is illustrated in the drawings in connection with the spindle-driving mechanism of an ordinary screw-cutting lathe. In this mechanism the spindle 8 is supported by ordinary bearings in the head 9 and carries a common cone-pulley 10, pinion 11, and gear 12, which are utilized to drive the spindle either directly or through the gears on the back gearing-shaft 13 in the usual manner. Keyed to the spindle is a gear 14, which meshes with a gear 15, that is in mesh with a gear 16 on the arbor of the gear 17, that is supported by the set-out stud 18 in the usual manner, Figs. 1 and 2.

The gear 17 meshes with a gear 19, that is

keyed to the hub of a gear 20, which is mounted to turn on a stud 21, that is held by a gear-box 22, that is clamped upon a bushing 23, which is fastened in the end of a gear-box 24. The gear 19 meshes with a gear 25, and the gear 20 meshes with a gear 26, so that the rotation of the gear 17 through the gears 19 and 20 rotates both the gears 25 and 26 in the same direction. In the mechanism shown the gears 19 and 25 are designed with a ratio of two to one and the gears 20 and 26 are designed with a ratio of one to two. The gears 25 and 26 are loosely mounted on the long hub 27 of a gear 28. This hub is supported by the bushing 23, and keyed to it are gears 29 and 30. In the outer end of the hub 27 is a key 31, that is hinged to the movable stud 32. When this stud is pushed in, as shown in Fig. 3, the gear 26 is keyed to the hub. Then the gears 28, 29, and 30 will be rotated by the gears 26 and 20 at the rate of one to two. When the stud is pulled out, the key connects the gear 25 with the hub, so that the gears 28, 29, and 30 will be rotated by the gears 25 and 19 at the rate of two to one. Thus by pushing in or pulling out the stud 32 two different relative speeds may be obtained between the set-out-stud spindle-gear 17 and the gears 28, 29, and 30 on the hub 27, Fig. 3. The gears 28, 29, and 30 mesh with gears 33, 34, and 35, which are loosely mounted on a shaft 36, Fig. 4. In this shaft is a key 37, that is adapted to be moved by a handle-lever 38, that extends upwardly through a gear-box, so as to connect either the gear 33, 34, or 35 with the shaft. The gears 28 and 33 are proportioned one to two, the gears 29 and 34 are proportioned one to one, and the gears 30 and 35 are proportioned two to one, so that by moving the handle 38 and changing the key three different relative speeds may be obtained between the hub 27 and the shaft 36.

Keyed to the shaft 36 is a gear 39, which meshes with a gear 40, the hub of which is supported by a bushing 41, that is set into a long sleeve 42, mounted in the lower part of the gear-case 24, Fig. 4.

Movable back and forth in and rotarily supported by the interior wall of the long sleeve 42 is a cylindrical carrier 43, which supports a spindle 44, that extends through and is connected by a feather with the hub of the gear 40, Fig. 3. Held against movement sidewise by the carrier, but having a free rotation therein, is a gear 45, that is keyed to the spindle 44. The cylindrical carrier as it

moves back and forth in the sleeve takes the gear 45 with it, and whatever the position of the gear 45 its spindle is always connected with and ready to be driven by the gear 40, which is driven by the gear 39 on the shaft 36.

Projecting outwardly from the cylindrical carrier through a slot in the sleeve is a frame 46, which carries a gear 47, that meshes with the gear 45, which is held by the carrier.

Extending outwardly from the frame through an opening in the gear-box is an arm 48, provided with a handle 49, that is adapted to be thrust toward the gear-box by a spring 50, so its inner end will project into one of the series of holes 51. When the handle is pulled out and dropped down, it can be moved so as to carry the frame and the carrier with the gears 45 and 47 to any desired position longitudinally of the sleeve. When the handle is moved to the desired locality, it can be lifted so the spring will force its end into one of the holes and keep it from further movement. This requires the gear 47 to remain correctly located. Keyed to the shaft 52, that has one end supported by a bushing 53 in the gear-box and the other end supported by the hub 27 inside of the gear-box, are gears 54, 55, 56, 57, 58, 59, 60, 61, and 62. Keyed to the outer end of the shaft 52 is a gear 63, that meshes with a gear 64, which is keyed to the end of the lead-screw shaft 65. By means of the handle the carrier may be moved back and forth in the interior of the sleeve until the gears 45 and 47 are opposite either of the gears 54, 55, 56, 57, 58, 59, 60, 61, or 62, and then by oscillating the handle the gear 47, which meshes with the gear 45, may be made to mesh with the gear which it is opposite.

On the inside of the gear-box, above the upper edge of the opening through which the arm 48 passes, is a rack 66, and on the edge of the arm is a lug 67, which when the gear 47 is in mesh with any of the cone-gears enters one of the openings of the rack, Figs. 6 and 7. In order to move the frame and carrier, the handle must be drawn out until its inner end is disengaged from one of the holes in the gear-box and must be dropped until the lug 67 is disengaged from the rack. Then the carrier and gear 47 can be moved longitudinally. The frame cannot be lifted for engaging the gears until the lug is opposite one of the rack-openings, and as a result of this the gear 47 cannot be engaged with any two of the cone-gears at the same time.

This changeable-speed feed mechanism may be connected with the feed mechanism of any ordinary machine-tool by securing the main gear-box to the bed, so that the gear 63 will mesh with the gear 64 on the lead-screw shaft, and then turning around the end gear-box until the gear 19, which it contains, meshes with the gear 17 on the set-out-stud shaft. After the end gear-box is properly

located it is clamped to the main gear-box, so as to keep its position.

By changing the position of the handle 49 a number of initial changes for the rotation of the lead-screw may be obtained. By moving the handle 38 these initial changes may be multiplied correspondingly, and by changing the stud 32 these changes may be still further multiplied. If the gear 19 is made to engage with the change-gear system of a common lathe, still further multiplications of the variations can be obtained.

All of the parts are simple to make. The cylindrical carrier has a long bearing in the interior of the sleeve, so that it will move back and forth easily and accurately with but little wear. There are no belts or friction devices in this mechanism. All of the drives are positively accomplished by direct gearing. The end gear-box can be swiveled to any desired position on the bushing which supports it. The change-gear shaft 52 has a long bearing in the hub, and as both travel in the same direction the surface speed, and consequently the friction, is much reduced. The whole device is compact and easily applied to any common form of machine the rate of feed of which it is desired to instantly change. There is but little machine-work to be done on the gear-cases and the supporting parts. There are no delicate parts to get out of order, and the arrangement is such that the gears cannot be engaged until they are in the proper position to mesh without jamming or becoming injured. If it is desired, the end gear-box can be left off and ordinary change-gears be utilized in its place.

The invention claimed is—

1. In a mechanism of the within-described class, in combination with a cone of gears, a sleeve located adjacent thereto and parallel therewith, a carrier supported by and movable longitudinally therein, a gear movable longitudinally with the carrier within the sleeve, and a gear movable longitudinally with the carrier without the sleeve and in constant mesh with the carrier-gear and adapted to be meshed with either of the cone-gears.

2. In a mechanism of the within-described class, in combination with a cone of gears, a fixed sleeve located adjacent thereto and parallel therewith, a carrier supported by and movable longitudinally and rotarily therein, a gear movable longitudinally with the carrier within the sleeve, and a gear movable longitudinally with the carrier without the sleeve and in constant mesh with the carrier-gear and adapted to be meshed with either of the cone-gears.

3. In a mechanism of the within-described class, in combination with a cone of gears, a sleeve located adjacent thereto and parallel therewith, a carrier supported by and movable longitudinally therein, a gear movable

longitudinally with the carrier within the sleeve, a frame movable longitudinally with the carrier, and a gear supported by the frame and in constant mesh with the carrier-gear and adapted to be carried by the frame into mesh with either of the cone-gears.

4. In a mechanism of the within-described class, in combination with a cone of gears, a longitudinally-slotted sleeve located adjacent thereto and parallel therewith, a carrier supported by and movable longitudinally within the sleeve, a gear movable longitudinally with the carrier within the sleeve, a frame connected to the carrier and extending through the slot in the sleeve, and a gear supported by the frame without the sleeve and in constant mesh with the carrier-gear and adapted to be meshed with either of the cone-gears.

5. In a mechanism of the within-described class, in combination with a cone of gears, a sleeve located adjacent thereto and parallel therewith, a carrier supported by and movable longitudinally therein, a shaft movable longitudinally with the carrier, a gear on said shaft and movable with the carrier within the sleeve, a gear movable longitudinally with the carrier without the sleeve and in constant mesh with the carrier-gear and adapted to be meshed with either of the cone-gears.

6. In a mechanism of the within-described class, in combination with a cone of gears, a sleeve located adjacent thereto and parallel therewith, a gear supported by and movable longitudinally therein, a frame extending outwardly from the carrier, a gear supported by the frame without the sleeve and in constant mesh with the carrier-gear and adapted to be meshed with either of the cone-gears, a handle for moving the frame, a lug projecting from the frame, and a fixed rack arranged to receive the lug and register the frame and the gear which it carries.

7. In a mechanism of the within-described class, in combination with a cone of gears, a sleeve located adjacent thereto and parallel therewith, a carrier supported by and movable longitudinally therein, a gear movable longitudinally with the carrier within the sleeve, a frame connected to and movable longitudinally with the carrier, a gear supported by the frame without the sleeve and in constant mesh with the carrier-gear and adapted to be meshed with either of the cone-gears, a handle for moving the frame, and a spring for causing the handle to engage a registering-hole and correctly position the frame and the gear which it carries.

8. In a mechanism of the within-described class, in combination with a lead-screw shaft, a driving-shaft, gears connecting the driving-shaft and the lead-screw shaft, a cone of gears keyed to the driving-shaft, a sleeve located adjacent to and parallel with the cone, a carrier supported by and movable longitudinally within the sleeve, a gear movable longitudinally with the carrier within the sleeve, and a gear movable longitudinally with the carrier without the sleeve and in constant mesh with the carrier-gear and adapted to be meshed with either of the cone-gears.

9. In a mechanism of the within-described class, in combination with a slotted sleeve, a carrier supported by and movable longitudinally therein, a shaft movable longitudinally with the carrier, a gear on said shaft and movable with the carrier within the sleeve, a gear movable longitudinally with the carrier without the sleeve and in constant mesh with the carrier-gear, and a gear splined to the longitudinally-movable shaft.

10. In a mechanism of the within-described class in combination with a slotted sleeve, a carrier supported by and movable longitudinally within the sleeve, a shaft movable longitudinally with the carrier, a gear on said shaft and movable with the carrier within the sleeve, a gear movable longitudinally with the carrier without the sleeve and in constant mesh with the carrier-gear, and a gear splined to the longitudinally-movable shaft.

11. In a mechanism of the within-described class in combination with a sleeve, a carrier supported by and movable longitudinally therein, a shaft movable longitudinally with the carrier, a gear on said shaft and movable with the carrier within the sleeve, a gear movable longitudinally with the carrier without the sleeve and in constant mesh with the carrier-gear, a shaft parallel therewith, a gear splined to the longitudinally-movable shaft, a gear on the parallel shaft meshing therewith, gears of different diameters loose on the parallel shaft, and a key movable in the latter shaft and adapted to connect either of the gears thereto.

12. In a mechanism of the within-described class in combination with a sleeve, a carrier supported by and movable longitudinally therein, a shaft movable longitudinally with the carrier, a gear on said shaft and movable with the carrier within the sleeve, a gear movable longitudinally with the carrier without the sleeve and in constant mesh with the carrier-gear, a gear splined to the longitudinally-movable shaft, a shaft parallel with the longitudinally-movable shaft, gears connecting the parallel shaft with the gear splined on the longitudinally-movable shaft, gears of different diameters loosely mounted on the parallel shaft, a key movable in the shaft and adapted to connect either of the gears with the shaft, a hub, and gears of different diameters secured to the hub and meshing with the gears loose on the key-shaft.

13. In a mechanism of the within-described class in combination with a sleeve, a carrier supported by and movable longitudinally therein, a shaft movable longitudinally with the carrier, a gear on said shaft and movable with the carrier within the sleeve, a gear movable longitudinally with the carrier without the sleeve and in constant mesh with the carrier-gear, a shaft parallel with the longitudinally-movable shaft, gears connecting these shafts, gears of different diameters loose on the parallel shaft, a key movable in the parallel shaft and adapted to connect either of the gears thereto, a hub, gears of

different diameters fast on the hub and meshing with the gears on the key-shaft, gears of different diameters loose on the hub, and a key movable in the hub and adapted to connect either of the loose gears thereto.

13. In a mechanism of the within-described class, in combination with a cone of gears, a sleeve, a carrier supported by and movable longitudinally thereto, a shaft movable longitudinally with the carrier, a gear on said shaft and movable with the carrier within the sleeve, a gear movable longitudinally with the carrier without the sleeve and in constant mesh with the carrier-gear, a gear splined to the longitudinally-movable shaft, a shaft parallel thereto, gears connecting the parallel shaft with the gear splined on the longitudinally-movable shaft, gears of different diameters loose on the parallel shaft, a key movable in the latter shaft and adapted to connect either of the gears thereto, gears of different diameters fixed to the same hub meshing with gears on the key-shaft, gears of different diameters loose on said hub, a key movable in the hub and adapted to connect either of the loose gears thereto, gears of different diameters meshing with said loose gears, and a driving-gear meshing with one of the latter gears.
14. In a mechanism of the within-described class, in combination, a hub having fixed gears of different diameters and loose gears of different diameters adapted to be keyed thereto, a shaft with one end extending into and supported by the hub, a cone of gears keyed to the shaft, a sleeve located adjacent to and parallel with the cone, a carrier supported by and movable longitudinally within the sleeve, a shaft movable longitudinally with the carrier, a gear fixed to said shaft and movable with the carrier within the sleeve, a gear movable longitudinally with the carrier without the sleeve in constant

mesh with the carrier-gear, a gear splined to the longitudinally-movable shaft, a shaft parallel with the longitudinally-movable shaft, a gear keyed to the said shaft and meshing with the gear splined to the longitudinally-movable shaft, gears of different diameters loose on the parallel shaft, a key movable in the parallel shaft and adapted to connect either of the gears thereto, said gears meshing with the gears on the hub.

15. In a mechanism of the within-described class in combination, a gear-box, a shaft in the gear-box, a cone of gears keyed to the shaft, a sleeve, a carrier movable longitudinally within the sleeve, a shaft movable longitudinally with the carrier, a gear on said shaft and movable with the carrier within the sleeve, a gear movable longitudinally with the carrier without the sleeve and in constant mesh with the carrier-gear and adapted to be meshed with either of the cone-gears, a bushing supported by the box, a hub rotatably mounted in the bushing, gears of different diameters fixed on the hub, loose gears meshing with the gears on the hub, a movable key adapted to connect these loose gears with a shaft, gears connecting this shaft with the longitudinally-movable shaft, a gear-box movably mounted on the bushing which supports the hub, and gears mounted in the latter gear-box for rotating the hub.

16. In a mechanism of the within-described class, in combination, a main gear-box, a cone of gears and gears for driving the cone-gears at different speeds in the gear-box, and an end gear-box, and gears in the end gear-box for driving the gears within the main gear-box, said end gear-box being rotarily connected with said main gear-box.
